UNITED STATES PATENT OFFICE.

GUSTAVE A. CARLSON, OF DETROIT, MICHIGAN.

CHAIN AND WHEEL FOR SASH-REGULATING DEVICES.

Application filed April 22, 1925. Serial No. 25,005.

To all whom it may concern:

Be it known that I, GUSTAVE A. CARLSON, a citizen of the United States, residing at Detroit, in the county of Wayne and State 5 of Michigan, have invented certain new and useful Improvements in Chains and Wheels for Sash-Regulating Devices, of which the following is a specification, reference being had therein to the accompanying drawings.

10 In my Patent No. 1,537,004, granted May 5, 1925, there is disclosed a sash regulating device of that type adapted to be used in the wall or door of a vehicle body for raising and lowering the sash or other closure relative to a window or door frame opening, and the device is of that type including a casing, a chain movable in the casing and adapted for shifting a sash or other closure, and a wheel for moving said chain, the wheel being 15 directly or indirectly driven from a crank operated arbor.

This invention has special reference to the chain and wheel drive of the sash regulating device and my invention aims to provide 20 a chain and wheel that will be exceedingly narrow so that it may be used in a small space. Ordinarily a sash well or compartment of an automobile is not very wide, consequently there is a limited space for sash 25 adjusting mechanism. It is desirable that the mechanism be as compact and narrow as possible so that it may be easily mounted in a sash well. An ordinary sprocket wheel and chain is very wide compared to my relatively thin chain and wheel, and I obtain 30 just as positive a drive as may be attained by an ordinary sprocket wheel and chain.

My invention further aims to provide as a 35 new article of manufacture, a wheel body cut and stamped from sheet metal to provide peripheral teeth with some of the teeth offset relative to the wheel body. The chain is composed of articulated single links of the same material as the wheel body and the 40 chain may be trained on the wheel, in driving relation thereto, with the greatest width of the driving device corresponding to two plies of material, that of the wheel and that of the chain link. This is in contradistinction 45 to wheels and chains made from castings or drop forgings and it is obvious that my chain and wheel can be produced at less cost with a saving in material and consequently less weight.

50 My invention will be hereinafter specifically described and then claimed, and refer-

ence will now be had to the drawing, wherein—

Figure 1 is a front elevation of the chain and wheel drive in connection with the sash 60 regulating device, the cover of the casing being removed;

Fig. 2 is a vertical sectional view of the device showing parts thereof in elevation;

Fig. 3 is a front elevation of a frame having a sash adjustable therein by a regulating device in accordance with this invention;

Fig. 4 is a perspective view of the detached wheel;

Fig. 5 is a front elevation of a portion of 70 the chain and wheel;

Fig. 6 is an edge view of the same, and

Fig. 7 is a perspective view of a portion of the chain.

In Fig. 3 there is shown a frame 1 having 75 a sash 2 slidable therein, and in the sash well 3 is a lock board or transverse member 4 adapted to support the device for adjusting the sash 2.

The sash regulating device includes an oblong casing 5 having a detachable cover 6. Slidable in the casing 5 is a chain composed of articulated links 7 with the lowermost link of the chain provided with an angular extension 8 for engagement with a rail 9 on the lower end of the sash 2. The chain links 7 are cut and stamped from rigid sheet metal and the ends of the links are apertured and rounded, as at 10, with rivets or other pivotal means 11 connecting the links of the 90 chain together. The links alternate in arrangement and the chain is only two-ply at such places where the ends of the links overlap.

The casing and its cover are provided with 95 bearings 12 for an arbor or shaft 13 having one end thereof provided with a crank 14.

Loosely mounted on the arbor 13 is the pressed out hub portion 15 of a wheel 16 and disposed about the arbor 13, at the side of 100 the wheel 16, is a clutch preferably in the form of an irreversible gearing generally designated 17, said clutch being actuated by the arbor 13 to impart rotation to the wheel 16 for sash adjusting purposes. The clutch or irreversible gearing is adapted to preclude any driving of the arbor 13 by the wheel 16, and the details of one form of irreversible gearing have been shown in my patent 105 above referred to. The form of clutch or irreversible gearing herein shown includes a stationary pressed out clutch member 18,

an inner clutch member 19, an eccentric 20 on the arbor 13, and a slotted plate 21 articulating the wheel 16 and the clutch member 19 and on the wheel 16 engaging in the slots of the plate 21. Such parts afford gyratory means of establishing a driving relation between the inner clutch member 19 and the wheel 16, but since this particular application is directed to the chain and wheel drive, 10 it is thought unnecessary to describe at length the operation of the clutch which establishes a driving relation from the arbor 13 to the wheel 16.

Considering the wheel 16, as shown in 15 Fig. 4, it is cut or stamped from rigid sheet metal, for instance that from which links 7 are made. Of course, other metal could be used and if so it is preferable to have the metal of the wheel the same gauge as 20 the metal of the chain links so that when the chain is trained about the wheel, as will hereinafter appear, there will be a comparatively thin driving device.

In producing the wheel 16 it is formed 25 with peripheral teeth 23 and 24 with the teeth 23 coextensive of the body of the wheel so that both sides of the teeth will be in the same planes as the sides of the wheel body. The teeth 23 alternate with the teeth 24 and 30 the latter are offset from one side of the wheel to form straight shoulders 25, the teeth 24 being offset a distance approximating the thickness of the metal wheel body, thus providing shoulders that are comparatively narrow and only of sufficient width 35 to allow the link 7 to obtain somewhat of a purchase on the shoulders. In forming these straight shoulders a hexagonal, octagonal or other geometrical shape is imparted to the 40 wheel and the teeth 23 and 24 are preferably greater in depth than the width of the link 7 so that the sides of the link 7 may readily coincide with the sides of the teeth.

In arranging the chain links on the wheel 45 alternate links are adapted to engage the shoulders 25 and by reference to Figs. 5 and 6 it will be noted that the pivoted ends of the links are positioned in the notches or spaces between the ends of the teeth 23 and 50 24 with the rounded edges 10 of the links engaging the end walls 26 of the teeth 23 and 24, thereby establishing a driving relation between the chain and wheel, irrespective of the engagement between the shoulders 25 55 and the longitudinal edges of the links 7. In practice, the shoulders 25 may constitute supporting means for the chain while the end engagement of the links and teeth constitute the driving relation. When the links 60 engage the shoulders 25 of the teeth 24, the links are in a plane with the body of the wheel and consequently there is a two-ply arrangement about the greater part of the

wheel, as shown in Fig. 1. As brought out 65 in Figs. 2 and 6 the chain and wheel drive is very narrow and it is in consequence of this relatively thin structure that the sash regulating mechanism does not occupy large 70 space in the sash well. With the casing and its cover made of sheet metal the entire structure is not very thick and as pointed out in the beginning this is a desirable feature in connection with any sash regulating device.

The wheel and chain constitute new articles of manufacture and I believe I am the 75 first to adopt a pressed sheet metal chain and drive for this particular art.

What I claim is:—

1. In a sash regulating device wherein a 80 sash is adapted to be raised by a chain trained over a wheel; a chain and wheel drive for such device, the wheel being comparatively flat and pressed from sheet metal to provide offset teeth, and the chain being composed of articulated flat links adapted to engage on alternate sides of the offset wheel teeth and have a driving relation established by ends of said links engaging end walls of said wheel.

2. A chain and wheel drive, as called for 85 in claim 1, wherein said wheel has a plurality of straight teeth in the same plane as one side of said wheel, and a plurality of teeth offset from the opposite side of said wheel, the offset teeth alternating with the straight 95 teeth and providing a chain channel about said wheel.

3. In a sash regulating device wherein a 100 sash is adapted to be raised by a chain trained over a wheel; a chain and wheel drive for such device, the wheel being comparatively flat and formed with teeth, some 105 of said teeth being in the same plane as the body of the wheel, and other teeth offset from the body of the wheel and alternating with the first mentioned teeth, the offset teeth affording shoulders, and chain links disposed so that alternate links engage said wheel shoulders and positions all of said chain links for end engagement with the ends of 110 said wheel teeth.

4. In a sash regulating device wherein a 115 sash is adapted to be raised by a chain trained over a wheel; a chain and wheel drive for such device, the wheel being comparatively flat and cut and stamped from sheet metal to form a thin wheel body and teeth, some of said teeth being offset from 120 said body a distance approximating the thickness of the sheet metal body, and chain links formed from similar wheel metal and operatively engaging said wheel so that the combined thickness of the chain and wheel drive approximates two plies of sheet metal.

In testimony whereof I affix my signature.

GUSTAVE A. CARLSON.
